UNITED STATES PATENT OFFICE.

SAMUEL T. NEWMAN, OF DANBURY, CONNECTICUT.

WIRE HAT RING AND STAY.

SPECIFICATION forming part of Letters Patent No. 361,833, dated April 26, 1887.

Application filed August 2, 1886. Serial No. 209,768. (No model.)

To all whom it may concern:

Be it known that I, SAMUEL T. NEWMAN, a citizen of the United States, residing at Danbury, in the county of Fairfield and State of Connecticut, have invented certain new and useful Improvements in Wire Hat Rings and Stays; and I do hereby declare the following to be a full, clear, and exact description of the invention, such as will enable others skilled in the art to which it appertains to make and use the same.

My invention has for its object to produce hat rings and stays made from wire or strips of metal. Heretofore, so far as I am aware, hat rings and stays have been made entirely from pasteboard, and ordinarily flanged upon one or both edges. Pasteboard rings and stays, however, are far from meeting the requirements of the trade, as they are expensive, bungling, and cannot be made to conform to the droop of the hat-brims.

By my invention I dispense entirely with the use of pasteboard and produce a light, cheap, and flexible ring or stay, which at the same time supports the hats perfectly and can easily be made to conform to the droop of the brims. In order to accomplish these results, I have devised the novel construction of which the following description, in connection with the accompanying drawings, is a specification.

Figure 1 is a perspective view illustrating my improved ring or stay in use, the hat being shown in dotted lines; and Figs. 2 and 3 are views illustrating different ways of joining the parts of the rings or stays together.

It will of course be apparent that my invention is not limited to any special style of forming the parts of rings and stays, but that they may be formed and may be joined together in any suitable manner, the essential features of my invention being a top ring, 1, a bottom ring, 2, and two or more braces or cross-pieces, 3, connecting the two rings. I have in practice found two braces or cross-pieces amply sufficient, and in order to produce a construction having a single brace or cross-piece on the opposite sides thereof I have formed the rings or stays of two separate parts or pieces of wire, both of which, however, are formed exactly alike, and are then joined together.

4 indicates a covering or envelope, of paper

or textile material, which I place about the wire in any suitable manner when the rings or stays are to be used in packing fine grades of light-colored hats.

5 indicates loops or projections, which I preferably form in the top or bottom rings, or in both. These loops or projections are made large enough to project out beyond the brims of the hats and to just fit within the boxes, so that when packed there will be no movement whatever of the stack of hats.

6 indicates the droop at opposite ends of both top and bottom rings in the completed rings or stays, which are so formed as to closely conform to the droop of the hat-brims.

I have found in practice that, owing to the elasticity of the wire, hats packed with my improved rings or stays may be very severely shaken about and may be handled quite roughly in transportation without damaging the hats in the slightest. For convenience in description I have designated the separate parts of which each complete ring or stay is formed as A and B. In the operation of forming each part is shaped to form one-half of a top and bottom ring, 1 and 2. These half-rings are formed in a plane approximately horizontal to the plane of the central portion of the wire, any desired droop being given to the half-rings in the process of manufacture. The central portion of each part, which I have indicated by 7, forms a portion of the cross-piece 3 of the completed ring or stay.

As stated above, the ends of each piece of wire and the independent parts A and B may be joined together in any suitable or preferred manner. In Fig. 1 I have shown the two ends 8 of each piece of wire bent toward each other after completing the top and bottom half-rings, 90 said ends lying in a plane parallel with portion 7, and being joined together by sleeves 9. This completes each independent portion of the ring or stay. The parts are then joined together by sleeves or bands 10, or in any suitable manner. As shown in Fig. 1, each cross-piece is formed by joining the portion 7 of one part to the ends 8 of the other part, which have previously been joined together by sleeve 9. In Fig. 2 the ends 8 of each part are carried past each other and are coiled about each other, and also about portion 7 of the other

part. In Fig. 3 the ends 8 are left shorter and are simply coiled tightly about portion 7 of the other part at top and bottom, this being, in fact, the simplest manner in which my improved ring or stay can be constructed.

I have not deemed it necessary to illustrate rings or stays formed of flat or curved strips of metal, as that is such an obvious equivalent of and substitute for the use of wire for this and analogous purposes.

Having thus described my invention, I claim—

1. A hat ring or stay consisting of top and bottom rings of metal connected by cross-pieces.

2. A hat ring or stay formed of metal and consisting of top and bottom rings connected by cross-pieces, one or both of said rings being provided with loops or projections 5, as 20 and for the purpose set forth.

3. A hat ring or stay consisting of top and bottom rings of metal joined together by cross-pieces, said rings and cross-pieces being provided with a paper or textile covering or an envelope, 4, as and for the purpose set forth. 25

4. A hat ring or stay consisting of top and bottom rings, 1 and 2, connected by cross-pieces 3, said ring or stay being formed from two pieces of wire, each of which is formed with a central portion, 7, two half-rings, and ends 8, which are connected to the central portion, 7, of the other piece. 30

In testimony whereof I affix my signature in presence of two witnesses.

SAMUEL T. NEWMAN.
